[57] CLAIM

The ornamental design for a housing for an electrical connector, as shown and described.

DESCRIPTION

FIG. 1 is a front and upper right perspective view of a housing for an electrical connector showing our new design;

FIG. 2 is a top plan view thereof;

FIG. 3 is a front elevational view thereof;

FIG. 4 is a bottom plan view thereof;

FIG. 5 is a right side elevational view thereof, the left side elevational view thereof being a mirror image;

FIG. 6 is a rear elevational view thereof; and,

FIG. 7 is a cross-sectional view thereof taken along line 7—7 of FIG. 3.

The broken line showing of the front and rear apertures is included for the purpose of illustrating environmental elements only and forms no part of the claimed design.
